Primary Examiner — Richard Edgar*Assistant Examiner* — David Truong(74) *Attorney, Agent, or Firm* — Oliff PLC(57) **CLAIM**

The ornamental design for a bottle as shown and described.

DESCRIPTION

FIG. 1 is a front elevational view of a bottle, showing the new design;

FIG. 2 is a rear elevational view thereof;

FIG. 3 is a left-side elevational view thereof, the right-side elevational view being a mirror image of the left-side elevational view;

FIG. 4 is a top plan view thereof; and,

FIG. 5 is a bottom plan view thereof.

The broken lines depict parts of the bottle that form no part of the claimed design. The dot-dash chain lines depict boundaries of the claimed subject matter and form no part of the claimed design.

1 Claim, 4 Drawing Sheets(56)
